UNITED STATES PATENT OFFICE.

HENRY SHERMAN LOUD, OF NEW YORK, N. Y., AND JOSEPH PANTER, OF STRETFORD, MANCHESTER, ENGLAND, ASSIGNEES TO THE WESTINGHOUSE MACHINE COMPANY, A CORPORATION OF PENNSYLVANIA.

TURBINE-BLADE.

941,375.

Specification of Letters Patent. Patented Nov. 30, 1909.

Application filed April 20, 1907. Serial No. 369,283.

To all whom it may concern:

Be it known that we, HENRY SHERMAN LOUD and JOSEPH PANTER, citizens of the United States, and residents, respectively, of New York, State of New York, United States of America, and Stretford, Manchester, in the county of Lancaster, England, have made a new and useful Invention in Turbine Blades and Vanes, of which the following is a specification.

This invention relates to elastic fluid turbines and more particularly to turbine blades and vanes.

An object of this invention is the production of effective means for mounting blades to the rotor and the vanes to the stator element of the turbine.

The rotary working elements of a turbine which receive the working fluid are ordinarily termed buckets, or blades and the stationary directing elements are termed vanes.

Our invention relates to means which are equally effective in mounting the blades in the rotor element or the vanes in the stator element, and for that reason, and also for the sake of brevity, we will herein-after use the term blade in a broad sense so that it will include both the rotating blades and the stationary vanes.

In the drawings accompanying this application and forming a part thereof; Figure 1 is a partial elevation of a portion of a blade shown in connection with a partial sectional elevation view of the mounting element. The blade is shown in the position it occupies just prior to being secured to the holding element; Fig. 2 is a similar view showing the positions of the parts after the blade has been secured to the supporting member; Fig. 3 is a side elevation of blades after they are mounted in accordance with the method illustrated in Figs. 1 and 2; Figs. 4 and 5 are views similar to Figs. 1 and 2 illustrating a modification of our invention; Figs. 6, 7, 8 and 9, are views similar to Figs. 1 and 2 and illustrate a still further modification of our invention.

In Figs. 1, 2 and 3 a method of mounting blades is disclosed in which the blade mounting element is provided with cylindrical holes into which the swaged ends of the blades are forced and in which they are se-

cured by being distorted. Each blade 20 is provided with a swaged end or shank 21, 55 which is adapted to more or less snugly fit into a substantially cylindrical hole 22 formed in the blade mounting element 23. Each hole 22 terminates at its inner end in an enlarged recess 24 in which a spherical 60 expansion piece or ball 25 is located. The ball 25 is adapted to contact with the inner end of the swaged portion of the blade before the blade reaches its final position. By forcing the blade into place the 65 ball 25 displaces the metal of the inner end of the shank 21, thereby causing the shank to be distorted or expanded to fill, or partially fill, the recess 24, the distortion of the shank causing it to grip the walls of the 70 hole 22. With such an arrangement the blades can be mounted on the mounting element 23 at any desired angle, as shown in Fig. 3, thereby overcoming the necessity of gaging after the blades are in place. 75

Figs. 4 and 5 illustrate a modification of our invention in which the expansion piece is formed integrally with the blade holding element and in which the swaged ends of the blades are notched, thereby 80 forming an initial opening into which the expansion piece is forced during the operation of mounting the blades. In this modification each blade 20 is provided with a swaged end 26, which is preferably of such 85 shape as to form a spacing piece between adjacent blades. The mounting element 23 is provided with an undercut slot 27 into which the blades are inserted for the purpose of mounting them to the element. Each 90 slot 27 is provided with a ridge 28, which is formed integrally with the mounting element on the inner face of the slot. The swaged end 26 of each blade is provided with a slot 29, which bifurcates the swaged 95 portion of the blade in such a way that it is caused to straddle the ridge 28 in entering the slot. In forcing the blades to place in the slot, the swaged portion is distorted by the ridge 28 and forced into gripping contact with each of the undercut walls of the slot by straddling the ridge 28. The width of the swaged end of the blade before it is mounted in the groove 27 is equal to the narrowest portion of the groove. In Fig. 5 100 the blade is shown in place, the bifurcated

ends being spread to straddle the ridge 28 and forced into gripping contact with the undercut walls of the slot.

In Figs. 6 and 7, a modification of this arrangement is shown. The end of the swaged portion 26 of each blade is provided with the slot 29 and the undercut groove 27, into which the blades are mounted, is provided with an expansion piece 28', 10 which, to all purposes, is the same as the expansion piece 28 shown in Figs. 4 and 5 except that it does not distort the swaged end of the blades to the same extent.

The operation of mounting the blades is 15 the same as that described in connection with Figs. 4 and 5; that is, the swaged end of each blade is inserted into the undercut slot 27 and forced to the bottom of the groove, thereby being secured in place by 20 the expansion or distortion of the swaged portion over the expansion piece 28'.

In Figs. 8 and 9 a modification is shown in which the expansion pieces are formed separately and inserted into the undercut 25 slots. Each blade 20 is provided with the swaged portion 26, which is provided with the slot 29. An expansion piece 31, which is wedge shaped in cross section, is located upon the inner face of the under cut slot 26, 30 which is formed in the mounting portion 23. The wedge shaped piece 31 is so located that its axis is parallel to the axis of the slot 27. In driving each blade 20 home into the slot 27, the slotted portion of the blade is

caused to straddle the wedge 31 and is distorted by it so as to grip the undercut walls 35 of the slot 27 by being forced into gripping contact with them.

What we claim is:

1. In an elastic fluid turbine, a blade holding element, a hole provided in said element, blades provided with slotted mounting portions and means, located within said hole, for distorting the mounting portion of said blade to grip the walls of said hole, whereby 40 the blades are secured to said holding element.

2. In combination in an elastic fluid turbine, a blade holding element, a hole provided in said element, blades provided with 50 slotted mounting portions and means, located within said hole and coöperating with said slotted portion, to secure said blade to said element.

In testimony whereof, we have hereunto 55 subscribed our names these 27th and 17th days of March and April, 1907.
